UNITED STATES PATENT OFFICE.

JAMES HARDMAN, JR., OF BELLEVILLE, NEW JERSEY, ASSIGNOR TO
THE INTERNATIONAL AUTOMOBILE AND VEHICLE TIRE CO., A COR-
PORATION OF NEW JERSEY.

DESIGN FOR RUBBER FABRIC.

No. 38,241.

Specification for Design.

Patented Sept. 18, 1906.

Application filed July 30, 1906. Serial No. 328,480. Term of patent 7 years.

To all whom it may concern:

Be it known that I, JAMES HARDMAN, Jr., a citizen of the United States, residing at Belleville, in the county of Essex and State of New Jersey, have invented a new, original, and ornamental Design for Rubber Fabric, of which the following is a specification, reference being had to the accompanying drawing, forming a part thereof.

The figure is a plan view of a piece of rubber fabric, showing my new design.

I claim—

The ornamental design for rubber fabric, as shown.

JAMES HARDMAN, Jr
